UNITED STATES PATENT OFFICE.

HENRY J. MILLER, OF GOSHEN, NEW YORK.

BORING AND TENONING MACHINE.

SPECIFICATION forming part of Letters Patent No. 268,118, dated November 28, 1882.

Application filed February 4, 1882. (No model.)

To all whom it may concern:

Be it known that I, HENRY J. MILLER, of the town of Goshen, in the county of Orange and State of New York, have invented certain new and useful Improvements in Boring and Tenoning Machines for Carriage-Makers, of which the following is a specification.

Said invention consists in the combination and arrangement of a horizontally-sliding drill-spindle in fixed bearings, which spindle carries the auger or tenon-cutter, and has an adjustable shoulder to set its sliding motion, and is furnished with bevel-gears for rotary motion, and provided with an automatic feeding device, and also an adjustable spoke-holder, an adjustable felly-clamp, and adjustable hub-clamp; and it consists, also, in the peculiar construction of the above parts, in combination with the whole, as hereinafter more fully specified.

In the drawings annexed, Figure 1 represents a side elevation of the machine constructed with my improvements. The spoke and hub clamps, the bench, and bearings of the drill-spindle are shown bisected. Fig. 2 is a detached side view of the spoke-clamp of the same. Fig. 3 is a top view of the hub-clamp of the same. Fig. 4 is a side elevation of the same, showing the felly-clamp in use and the bench and felly-clamp bisected. Fig. 5 is a top view of the same. Fig. 6 is a detached cross-section of the felly-clamp. Fig. 7 is a detached cross-section of the hub-clamp. Fig. 8 is a detached perspective view of the adjusting-wedges or wedge-slides.

A, Fig. 1, represents the working table or bench. Upon it are arranged the bearings B B', in which the horizontal sliding drill or boring-spindle C is rotated. Said spindle has on its forward end the drill-head provided with a set-screw to secure the auger D for boring, and when used for tenon-cutting the tenon-cutter E is secured in said head in place of the auger, and at the forward bearing, B', is fitted, over said spindle a beveled pinion, F, which revolves in said bearing, but is held longitudinally to the same by means of a shoulder over each end of the bearing. The pinion F is furnished with a feather or key to engage in the groove C', so as to cause the spindle to turn with the pinion, but allowing the spindle to slide freely through the same. The rotation of the pinion is caused by means of a beveled gear, G, which is furnished with a bearing-stand, H, and a short shaft, to which a hand-

crank, L, is attached, so that by turning with 55 the hand-crank the gear G rapid motion is imparted to the pinion F and the spindle C.

Upon the rear end of the spindle is employed a fly-wheel, J, to obtain momentum and equal speed, and consequently facilitating the 60 labor. On said fly-wheel is furnished a set-screw, X, to adjust the said wheel at the desired distance from the rear bearing, B, and thereby serve as a stop for the auger or tenon-cutter, to stop it from cutting deeper than required. A short distance backward from the 65 drill-head said spindle is furnished with a loose cross-head, K, which is held between two shoulders formed on the spindle, and allows the spindle to turn loose therein.

L' represents a vertical lever, which is pivoted to the lug or eyebolt M, secured to the bench, and said lever is slotted, so as to pass over the cross-head K, which has a trunnion on each side projecting into the lever to engage 75 it, and thereby causing the sliding of the spindle, with the auger, from or toward the work with the lever L'.

In order to cause the automatic feeding of the auger or tenon-tool, I employ the standard 80 M', which carries one rope-pulley, N, in the top end, and one, N', near its lower end. A weight, O, is attached to the bottom end of a rope, P, which passes over the pulleys N and N', and has its top end secured to the top end 85 of the lever L'. Consequently said weight draws the lever and spindle forward, and thereby feeds the auger or tenon-cutter until the fly-wheel stops against the rear bearing, as aforesaid. To withdraw the auger or cutter, the 90 operator presses the said lever back.

R represents the hub-clamp, S the spoke-clamp, and T the felly-clamp, which are all arranged upon the bench, which is provided with central longitudinal slots, U, to adjust them to 95 the desired distance from the auger or tenon-tool, and each of them is furnished with a screw and tightening or thumb nut, V, under the bench to secure the clamp thereto while in use. The spoke-clamp S is constructed with 100 a semicircular fork on its top end, in which the spoke is received. A semicircular bent hand-lever, s, is pivoted to the one prong of the clamp and drops over the spoke into the 105 opposite prong, which is slotted open on its top end for the purpose. By pressing the lever s down the spoke is firmly clamped. The lower part of this clamp is made with a vertical rod,

b, which is threaded from a distance above the bench, and over the threaded end is fitted the adjusting-nut *c*, to form a shoulder for the clamp to rest upon the bench, so that by raising and lowering said nut *c* the clamp is adjusted to the required height. On the bottom end is applied the thumb-nut *V*, to secure the clamp upon the bench. The hub-clamp *R* is constructed with a base-block, *W*, which rests upon the bench, and has a bolt to pass through the slot *U*, and is furnished under the bench with the thumb nut *V*, to secure it firmly thereupon. A guide-pin, *d*, is also secured in the bottom of said base-block *W*, projecting into the slot *U* of the bench to guide said block in moving it properly. The top of said block has two upright opposite guide-posts, *e e*, over which a top plate, *f*, is fitted, it having a central vertical stud or bolt, *g*, by means of which the hubs of the wheels are secured. Said bolt has on its top end the thumb-nut *h*, and said top plate, *f*, has a slot for each of the guide-posts *e* to pass readily through the same, and thereby guide the plate in its up-and down motion. Between the block and said plate *f* is employed a pair of wedge-slides, *i i*, which are attached together, as shown in Fig. 8, and they are fitted in grooves formed on the block, and the plate *f* rests upon them. Consequently by sliding the wedge-slides *i i* toward the auger the plate *f* is raised, and moving the wedge-slides rearward said plate is lowered, so that by this means the hub-clamp is very readily adjusted to the proper height required, and by means of the slot in the bench the clamp is readily adjusted to the proper distance from the tenon-cutter. A set-screw, *j*, is employed on the block to hold the wedge-slide firmly while cutting the tenon.

To hold the auger or tenon cutter off from the work, I employ the ratchet *k* on the bottom end of the lever *L'*, and a pawl, *l*, is pivoted to the bench, which pawl engages the ratchet and holds the lever until desired to liberate and allow the weight to feed the auger. The felly-clamp *T* is constructed similar to the hub-clamp. It has a base-plate, *m*, furnished with a holding-down bolt to pass in the slot of the bench, provided with a thumb-nut, *V*, underneath. It has also a guide-pin in said slot. The base-plate is made with vertical guide-posts *a a*, in which the table *n* is laterally guided while raised or lowered. Between this table and the base-plate *m* are employed the pair of wedge-slides *i* for adjusting the table to the desired height. The guide-posts *a a* have grooves to guide the wedge-slides *i*, and said posts *a a* are united on their top ends with a cross-piece *p*, to which the clamping-screw *r* is attached by means of a threaded plate *y*. The felly is clamped upon the table *n*, which is furnished with the adjustable guide-plates *t t* to locate the felly accurately in the proper direction for boring. The plate *y* is slotted to adjust the clamping-screw proper for the felly.

Instead of using the hub with the set-screw

x formed on the fly-wheel *J*, a detached collar with a set-screw may be used as a stop to determine the sliding motion of the spindle *C*. When the tenons are to be cut all the spokes are inserted into their hub, which is held into the hub-clamp, and said fly-wheel *J* (or, if a detached collar is used, said collar) is so adjusted on the spindle *C* that the tenon-cutter accurately forms the shoulder of the tenon at the spoke, wherever the felly is to rest. By cutting the tenon of each spoke of the wheel and stopping with the said collar properly, the shoulders of the tenons are all made equidistant from the center of the hub of the wheel, and thus the fellies, when placed, come to a true circle at once. By means of the wedge-slides *i i*, connected together and applied as shown, the table for cutting and boring the fellies is raised in vertical direction in a manner to retain a solid broad bearing. Fellies are very readily adjusted to the proper height, although having different thickness. The relative distance of the felly from the drill is not altered in the clamp on account of its thickness. The wedge-slides *i i* can be marked, so that they need only be placed to the mark and answer at once a number of fellies, and at any time secure the felly to its proper place without particular examination of adjustment.

I do not claim any of the features alluded to in the Letters Patent granted to Reid and Pierce, No. 112,279, dated February 28, 1871.

What I claim as my invention, and desire to secure by Letters Patent, is—

1. In boring-machines for carriage and other wood-work, the arrangement of the sliding spindle *C*, with its fly-wheel and beveled pinion and gear *G'*, the lever *L'*, pulleys *N*, and weight *O*, to feed the auger or tenon-cutter automatically, in combination with the adjustable spoke-clamp *S* and adjustable hub-clamp *R*, substantially as and for the purpose herein set forth.

2. The combination and arrangement of the sliding spindle *C*, its fixed bearings, and the feed-lever *L*, its rope and weight, with the ratchet *k* and the pawl *l*, the tenon-cutter, the hub-clamp and its wedge-slides *i i*, and the spoke-clamp *S*, substantially as and for the purpose herein set forth.

3. The construction and arrangement of the felly-clamp *T*, with its base-plate *m* and its holding-down bolt, its vertical guide-posts *a a*, the table *n*, with the coupled wedge-slides *i i*, and the guide-plates *t t*, substantially as and for the purpose herein described and shown.

4. The combination and arrangement of the wedge-slide *i*, the felly-clamping table *n*, with its guide or guides *a a*, and the clamping-screw *r* and base-stock *m* and its thumb-screw nut *V*, substantially as and for the purpose herein described.

In witness whereof I have hereunto set my hand this 23d day of December, 1881.

Witnesses: HENRY J. MILLER.
